UNITED STATES PATENT OFFICE.

GILBERT C. McCULLOUGH, OF DETROIT, MICHIGAN, ASSIGNOR TO PREMIER PRODUCTS COMPANY, OF DETROIT, MICHIGAN, A CORPORATION OF MICHIGAN.

UPHOLSTERY-FILLING DEVICE.

Application filed April 24, 1925. Serial No. 25,565.

This invention relates to tubular cores for the purpose of inserting cotton batts or other filling material into tubular envelopes, such as the pleats of upholstery, its object 5 being to provide for the operation of the core in a special manner intended to facilitate the handling of the filling material inserted by the core into a tubular envelope and the removal of the core from the envelope after the insertion of such filling, the 10 said invention being a modification or improvement of the device disclosed and illustrated in my co-pending application, Serial No. 25,566 filed April 24, 1925.

15 The said invention resembles that disclosed in the said co-pending application referred to in that it comprises a longitudinally divided tube, one part of which is capable of contraction or expansion relative to the other 20 part thereof so that the cross sectional area may be varied to all intents and purposes throughout the length of the tube and a tubular flared receiver is provided through which filling material may be entered into 25 the tube, but in the present device the upper member of the tube is not recessed or cut away at the forward end thereof to give access to the filling material so that it may be held while the said core is withdrawn 30 from a pleat; the present invention having as one of its objects to dispense with such openings or recesses at the forward end of the core so that the filling material will be effectively enclosed at this point when being introduced into a tubular envelope and 35 such introduction rendered easier of accomplishment. The said invention further aims to provide for the movement of one of the members longitudinally with respect to the 40 other of the members prior to the withdrawal of the core from the tubular envelope so that manual pressure may be applied to the end of the filling material in the desired manner.

45 It is also an object of the said invention to provide means whereby this sliding of one of the core members with respect to the other may be effected in an unobtrusive or practically automatic manner by an operator as 50 a result of the action of pulling on the device to effect its removal from a tubular envelope; the invention, to that end, con-

templating the use of a slide mounted upon that portion of the device which is grasped and pulled in effecting a removal of the 55 core, such slide being connected to a movable member of the core whereby the said pulling action will be transmitted to said movable member and effect its rearward sliding relative to the other member of the core 60 prior to the entire removal of the said core from the tubular envelope.

Still further objects subsidiary to or resulting from the aforesaid objects, or from the construction or operation of the said invention as it may be carried into effect, will 65 become apparent as the said invention is hereinafter further disclosed.

In carrying the said invention into effect I may provide a tubular core longitudinally 70 divided into upper and lower opposed trough-shaped members having their outer ends normally flush with one another, a flared tubular handle portion or receiver being adapted to the rearward end of the lower 75 trough-shaped portion and acting as the guide through which filling material is fed to the said divided tubular core, and a slide longitudinally movable on said receiver and adapted to be grasped with the receiver by 80 an operator, said slide being connected, as by a compound hinge, to the upper trough-shaped member of the divided tubular core whereby the said upper member may be moved rearwardly of said lower member by 85 an operator in the act of effecting withdrawal of the core from a tubular envelope.

All of which is more particularly described and ascertained hereinafter, by way of example, having reference to the accompanying drawing, wherein—

Figure 1 is a plan of a tubular envelope-filling core embodying the said invention;

Figure 2 is a side elevation of the same;

Figure 3 is a similar view to Figure 2, 95 with the parts in a relatively varied position;

Figure 4 is a fragmentary vertical section of the device, with the parts in the positions indicated in Figure 3; and

Figure 5 is a fragmentary plan view of the forward end of the core with the parts in the positions indicated in Figure 3.

Similar characters of reference indicate

similar parts in the several figures of the drawing.

The core proper is indicated as being in the form of a longitudinally divided tube having upper and lower trough-shaped members 1 and 2, the lower member being provided with a rearwardly extending flared tubular portion 3 through which filling 4 may be fed to the tube, and which portion 10 may be utilized as a hand grip by an operator in filling tubular envelopes.

Normally, as will be apparent from Figures 1 and 2, the forward end of the upper member is flush or approximately flush with 15 the forward end of the lower member so that the said forward ends of the tube members substantially embrace the filling material at this point, and in the operation of filling tubular envelopes the parts are maintained in 20 these relative positions while the core is inserted into the envelope and therefore little contact is established between the filling and the envelope during such operation.

It is, however, desirable that provision be 25 made for permitting pressure to be applied through the envelope to the end of the filling during the extraction of the core from the envelope to prevent the filling being also extracted, and for such purpose I have provided for the rearward movement of the member so that the forward end of the filling will be uncovered by the said upper member.

To facilitate such movement of the said 35 upper member I indicate it as being attached, preferably by a compound hinge member 5, to a slide 6 having tongues 7 entering elongated slots 8 in the member 3. This slide is also provided with an upwardly projecting tongue or abutment 9 at its rear end so that, in the gripping of the member 3 by the operator in utilizing the said core, the hand extends over the said slide 6 and engages the abutment 9. It will be obvious that this arrangement permits of the 45 upper member 1 of the core being drawn rearwardly in the suggested manner by the action of the hand in commencing to move the core rearwardly to withdraw it from a tubular envelope, thus effecting a preliminary retracting of the said upper member 1, upon the completion of which retraction the further movement of the hand in the same direction results in the rearward movement 50 of the core as a whole.

The retracted position of the upper member is well illustrated in Figure 3, which shows the disclosure of the forward end 9 of the filling. A tubular envelope 10 is indicated in dotted lines in Figures 2 and 3.

The disclosed arrangement facilitates the insertion of filling into a tubular envelope by enclosing it substantially at the forward end, although providing, at the time required, facility for engaging the end of the

filling during the retraction of the core from said envelope and is of a simple and positive operable nature very unlikely to get out of order and admitting of cheap construction.

This invention may be developed within the scope of the following claims without departing from the essential features of the said invention, and it is desired that the specification and drawing be read as merely illustrative and not in a limiting sense, except as necessitated by the prior art.

What I claim is:—

1. A device for the insertion of filling into tubular envelopes, comprising a tubular receiver, a lower elongated trough-shaped member extending forwardly of said receiver, and an upper member extending thereover from said receiver to the forward end of said lower member and slidably rearwardly relative thereto.

2. A device for the insertion of filling into tubular envelopes, comprising a tubular receiver, a lower elongated trough-shaped member extending forwardly of said receiver, and an upper inverted trough-shaped member extending thereover from said receiver to the forward end of said lower member and slidably rearwardly relative thereto.

3. A device for the insertion of filling into tubular envelopes, comprising a tubular receiver, a longitudinally divided tubular core comprising upper and lower members, the lower member rigidly extending from the forward end of said receiver, and the upper member being slidably connected to said receiver whereby it is rearwardly movable over said lower member.

4. A device for the insertion of filling into tubular envelopes, comprising a tubular receiver, a lower elongated trough-shaped member extending forwardly of said receiver, and an upper member extending thereover from said receiver to the forward end of said lower member, a rearwardly slid- 110 able member on said receiver, and a hinge connecting said upper member to said slid- able member.

5. A device for the insertion of filling into tubular envelopes, comprising a tubular receiver, a lower elongated trough-shaped member extending forwardly of said receiver, an upper member extending thereover from said receiver to the forward end of said lower member, a rearwardly slid- 115 able member on said receiver adapted to be grasped by the hand of an operator, an abutment on said slidable member whereby rearward movement of the hand relative to said receiver may be imparted to said member, and means connecting the upper member of said core to said slidable member.

6. A device for the insertion of filling into tubular envelopes, comprising a tubular re- 120

ceiver, a lower elongated trough-shaped member extending forwardly of said receiver, an upper member extending thereover from said receiver to the forward end of said lower member, a rearwardly slid able member on said receiver adapted to be grasped by the hand of an operator, an abut-

ment on said slid able member whereby rear ward movement of the hand relative to said receiver may be imparted to said member, and means hingedly connecting the upper member of said core to said slid able member. 10

In testimony whereof I affix my signature.
GILBERT C. McCULLOUGH.
